UNITED STATES PATENT OFFICE.

LEWIS S. CHILSON, OF ATTLEBORO, MASSACHUSETTS, ASSIGNOR TO J. M. FISHER COMPANY, OF ATTLEBORO, MASSACHUSETTS, A CORPORATION OF RHODE ISLAND.

BRACELET HOOK.

Application filed October 6, 1924. Serial No. 741,912.

To all whom it may concern:

Be it known that I, LEWIS S. CHILSON, a citizen of the United States, residing at Attleboro, in the county of Bristol and State 5 of Massachusetts, have invented certain new and useful Improvements in Bracelet Hooks, of which the following is a specification.

This invention relates to an improved construction of bracelet hook, more particularly adapted for attaching the ends of a bracelet to a wrist watch and the like; and the object of this invention is to provide a simple and practical construction of such a hook comprising a body member and a 15 separate tongue member, one end of the tongue member being secured to the adjacent end of the body with the free-forward end of the tongue yieldably closing the hook.

With these and other objects in view, the 20 invention consists of certain novel features of construction, as will be more fully described, and particularly pointed out in the appended claims.

In the accompanying drawings:

25 Figure 1 is a rear view of a watch showing my improved form of hook as engaging the bail thereof and as connected to an adjacent bracelet element.

Figure 2 is a perspective view showing 30 the under side of the hook with the spring tongue removed therefrom.

Figure 3 is a perspective view of the 35 spring tongue removed from the hook member.

Figure 4 is a central sectional longitudinal view through the hook and the tongue member secured in the body member and the latter member connected to an adjacent bracelet element.

40 Figure 5 is a section on line 5—5 of Figure 4.

It is found in the practical construction and operation of hook members of this character, of advantage to provide a body 45 member of sheet stock having a hook at one end and side walls adjacent its opposite end and to provide a tongue member having side walls at one end which are adapted to be engaged by the walls of the hook member

50 for the purpose of rigidly supporting the tongue in the body member, the forward end of the tongue member being free to yieldably close the hook, the side walls of the tongue member being turned slightly inwardly to stiffen the spring action of the

tongue; and the following is a detailed description of the present embodiment of my invention and showing one means by which these advantageous results may be accomplished:—

With reference to the drawing, 10 designates the body member of the hook, which is provided with rearwardly-turned side walls 11, and a neck portion which is flared outwardly towards its opposite or hook end 60 the stock of which is folded rearwardly to form hook-shaped fingers 12 which are adapted to engage the bail of a watch or other member. This body member is also provided at its rear end, with a finger 13 adapted to be folded or rolled through an opening 14 in an adjacent bracelet member 15, as shown in Figure 4, to hingedly connect the two together.

In order to yieldably close the mouth of the hook, I have provided a spring tongue member 16 which is also preferably formed of sheet stock, the same having its opposite side walls being adapted to fit between the side walls 11 of the body portion and the edges 18 of the body walls 11 are turned over the corresponding body portion of the tongue as shown in Figure 5, to securely lock the two members together.

The bottom edges 19 of the tongue flange are preferably beveled on a slight angle to the plane of the back of the tongue so as to incline the free end of the tongue upwardly and also to provide a bearing for the tongue against the inner corresponding surface 20 65 of the body member to support spring action of the free end 21 of this tongue, the forward end of the tongue being arranged to engage the under side of the hook-shaped fingers with a yielding pressure whereby it 70 may be pressed inwardly when desired to permit the bail to enter or leave the hook when it is desired to connect or disconnect the hook to said bail or other element.

In some instances, it is found of advantage 75 in order to stiffen the action of the spring tongue to provide a narrow downwardly-extending flange portion 22 on the opposite side edges of the tongue so that its resistance to being opened against pressure will be increased to the desired extent.

I have herein shown a rear edge wall 23 formed on the tongue to extend down towards the rolled end 13 of the body member to close this end.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

- 10 1. A sheet metal bracelet hook comprising a body member bent at one end to form a hook and having side walls adjacent its opposite end and a separate spring tongue member having one end rigidly supported by said side walls and having its forward end free and extending to yieldingly close the mouth of the hook portion.
- 15 2. A sheet metal bracelet hook comprising a body member bent at one end to form a hook and having side walls adjacent its opposite end, and a spring tongue member having side walls adjacent one end thereof set inside of those of the body member and secured thereto, the forward end of said tongue being free and extending into position to yieldably close said hook.
- 20 3. A sheet metal bracelet hook comprising a body member bent at one end to form

a hook, and a spring tongue member having supporting flanges adjacent one end thereof and rigidly connected to said body member, the opposite end of said tongue being free and extending forwardly to yieldingly close the hook.

35 4. A sheet metal bracelet hook comprising a body member bent at one end to form a hook and having a bendable member at its other end for connection with the next adjacent element, and a spring tongue member having supporting flanges adjacent one end thereof and rigidly connected to said body member, the opposite end of said tongue being free and extending forwardly to yieldingly close the hook.

40 5. A sheet metal bracelet hook comprising a body member bent at one end to form a hook and having side walls adjacent its opposite end, a spring tongue member fixed at one end to said body member, the forward end of said tongue extending to yieldably close said hook, and a member on the tongue serving as a fulcrum to assist in supporting the free end of the tongue in 45 operating position.

In testimony whereof I affix my signature.
LEWIS S. CHILSON.
